(57) **CLAIM**

The ornamental design for a candle warmer, as shown and described.

DESCRIPTION

FIG. 1 is a front perspective view thereof;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan thereof; and,

FIG. 7 is a bottom plan thereof.

The electric cord and cord openings on the bottom of the candle warmer are shown in broken lines and form no part of the claimed design.
